UNITED STATES PATENT OFFICE

146,774

DESIGN FOR A MAN'S SPORT SHOE OR SIMILAR ARTICLE

Ralph A. Parker, Melrose, Mass.

Application November 9, 1946, Serial No. 134,642

Term of patent 14 years

(CL. D7—7)

To all whom it may concern:

Be it known that I, Ralph A. Parker, a citizen of the United States of America, residing in Melrose, in the county of Middlesex and Commonwealth of Massachusetts, have invented a new, original, and ornamental Design for a Man's Sport Shoe or Similar Article, of which the following is a specification, reference being had to the accompanying drawing, forming a part thereof.

Fig. 1 is a plan view of a man's sport shoe embodying the invention;

Fig. 2 is a right-hand side elevation of a man's sport shoe as shown in Fig. 1; and

Fig. 3 is a left-hand side elevation of a man's sport shoe shown in Fig. 1.

I claim:

The ornamental design for a man's sport shoe or similar article, substantially as shown.

RALPH A. PARKER.
